UNITED STATES PATENT OFFICE.

HILDEGARD DOEDERLEIN, OF WOODRIDGE, NEW JERSEY.

CURTAIN TAPE.

Application filed January 11, 1927. Serial No. 160,352.

This invention relates to curtain hangers and it particularly relates to hangers in the form of loops.

Up to now all curtains are hung up uniformly by means of safety pins put into the hems in curtains and having their hook-shaped upper end then inserted into the eye of either a wooden or metal ring which is then slipped over a curtain-pole. Inasmuch as it takes quite a number of such rings to properly hang up a curtain, and inasmuch as it takes a considerable number of safety pins and metal rings, which in the meantime either get rusty or become tarnished, for renewal at certain intervals, such a condition causes an expense which is much felt because everybody sees that it should and probably could be avoided; in addition the curtain gets spoiled by the rust on the needles. Moreover, the work of taking off the pins from the rings and from the curtains and to subsequently fix them on again on the new curtain, causes a burden for the housewife, who has to manage without help, and an article which will avoid this burden and will save the housewife time and money, has been an urgently felt want of long standing.

It is an object of the invention to give the housewife relief from this work and to create an article which, though it is intended to be made on a large scale at a moderate price, is of pleasing and attractive appearance and which reduces the work of hanging up curtains to such an extent that it is accomplished with great facility.

It is an object of the invention to make a curtain-hanger, instead of metal or wood requiring much handling to be brought into the desired shape, from cotton or silk, artificial silk, or any other vegetable, animal, or artificial fiber which can be worked by hand, or, on the largest scale by machines, such as knitting, crocheting, embroidery or any other machines for such purposes.

It is an object of the invention to make a curtain hanger which, once attached or joined to the curtain by sewing, or any other stitching process whatever, can permanently stay in this fixed relation with the curtain without the necessity of even temporarily severing it from the same.

It is further an object of the invention to create a curtain-hanger which, being made mechanically by machine work, can be sold

at a moderate price by the yard; that in view of its moderate cost of production, it can be sold in varying measurements so as to fit curtain poles of varying diameters.

It is also an object of the invention to create a curtain-hanger which can be washed or cleaned in any other suitable way together with the curtain without separating it therefrom.

It is another object of the invention to create a curtain-hanger which similarly to being washed with the curtain can be dyed, either with the curtain already attached thereto or separately from the same, in any color whatever.

It is an object of the invention to create a curtain-hanger which after its attachment to the curtain remains in a permanent relation with the same; that, given the same quality of goods in both, it is as long lasting as the curtain proper, that it can be slipped over the curtain pole and saves the housewife the expense of time formerly wasted with disengaging and re-joining the various holding members and saves the expense of exchanging members having tarnished thereby detracting from the ornamental appearance of the curtain.

It is also an object of the invention to create a curtain-hanger which can be manufactured in plain as well as in luxurious styles to suit any kind of a home.

With these objects in view, reference is had to the accompanying drawings, in which

Figure 1 is a front elevation, slightly perspective, showing a loop curtain-hanger depending from a curtain-pole, and

Figure 2 is a vertical sectional view on the line 1-1 of Figure 1, the section going through the center line of the front and rear part of a loop to show the integral connection of the loops with the strip.

Referring to the drawing the numeral 10 denotes a curtain-pole of one of the usual styles over which are slipped a number of loops 11, each preferably equidistant from each other. These loops may be of any width, which depends largely on the length and width of the curtain and therefore on the weight they have to bear; the width of the curtain governs also the number of loops with which each curtain is provided and whether the curtain is to hang smoothly, or to form folds. I may say that approximately $1\frac{1}{2}$ to $1\frac{1}{4}$ " is a fair measurement of the

width of the loops in most cases and that approximately $3\frac{1}{2}$ distance between two adjoining inner edges of loops will guarantee a smooth and pleasing appearance of the curtain; if it is to show light folds, this distance may be varied until the desired effect is obtained.

It will be noticed from an inspection of both figures of the drawing that the loops 10 11 are integrally connected with the strips 12 as is obvious for instance from the thread 13 running upwardly through said strip 12 and then through the loop 11 from where it is conducted back to the strip 12 by the 15 knitting or other mechanical working process. 14 denotes a curtain secured to the strip 12 by means of one or a plurality of stitch lines 15 so as to permanently affix the curtain and its holder together; this 20 having been done, the loops are slipped over the pole which then is mounted upon its supporting brackets (not shown). The loops 11 are all equally long.

It will further be noticed from an inspection of the drawing that a plane put through the longitudinal center line of the front and rear parts of any of the loops will be perpendicularly disposed on the plane of the curtain.

30 In contradistinction to such a modifica-

tion of my invention as just described I beg to specifically point out that in the loops as illustrated in the accompanying drawing the front and rear parts, as is obvious, are not disposed aside of, but behind so as to cover 35 each other. Moreover, though it is chiefly intended to make the strip and the loops integrally connected therewith, as a separate article of manufacture, it is possible to integrally join the loops with the curtain during its manufacture and any such curtain having loops integrally connected therewith, is also claimed as being within the scope of the invention.

What I claim is:

1. A curtain tape adapted to be secured at the upper edge of a pendant curtain, said tape comprising an elongated fabric strip adapted to extend the width of the curtain and provided with spaced integral loops 50 extending from the upper edge thereof.

2. A curtain tape adapted to be secured at the upper edge of a pendant curtain, said tape comprising an elongated fabric strip adapted to extend the width of the curtain 55 and provided with spaced reinforced integral loops extending from the upper edge thereof.

HILDEGARD DOEDERLEIN.
